 his Atty.

UNITED STATES PATENT OFFICE.

GEORGE L. MENK, OF ST. LOUIS, MISSOURI.

AIR COOLING AND CIRCULATING DEVICE.

1,424,843.

Specification of Letters Patent.

Patented Aug. 8, 1922.

Application filed March 20, 1919. Serial No. 233,856.

To all whom it may concern:

Be it known that I, GEORGE L. MENK, a citizen of the United States, residing in the city of St. Louis and State of Missouri, have 5 invented a new and useful Improvement in Air Cooling and Circulating Devices, of which the following is a specification.

This invention relates to air cooling and circulating devices. It has for its objects to 10 produce a novel apparatus or device which may be made attractive and ornamental in appearance as well as structurally efficient to cool and circulate the air in an auditorium, theatre, or other room or place of assembly where it may be desirable to reduce the 15 temperature.

The invention consists essentially in a hollow column or vertically disposed tubular shell through which the air is drawn in at 20 the base portion thereof and passed in contact with a cooling agent or medium by mechanical means, and thence forced out laterally at or near the top. It further consists in the parts and in the combinations and 25 arrangements of parts as set forth in the following description and afterwards pointed out with particularity in the appended claims.

A practical adaptation of the invention is 30 illustrated in the accompanying drawing, the sole figure of which shows the apparatus in vertical section.

Referring now to this drawing, the numeral 1 designates the hollow column or 35 vertically disposed tubular shell which may be constructed of sheet metal, wood or other suitable material. As shown, the column is made sufficiently large in diameter at its base to afford a steady footing, and it is prefer- 40 ably tapered towards the top so as to avoid top-heaviness.

Above the restricted throat 2 where the taper ceases, the shell is flared, as at 3, to constitute a mouth, and cooperating therewith is a cover-plate or closure 4, the marginal portion of which projects beyond the circumference of the lip and serves as a deflector as will later more fully appear.

The cover-plate or closure 4 may be ad- 50 justably mounted in any desirable manner, but, as shown, it is preferably provided with a screw-threaded axial stem 5 which works through a spider or other suitable support 6 provided therefor within the mouth or the 55 throat of the column; and a knob 7 is provided for convenience in manipulation.

In the lower part of the hollow column 1 is a frusto-conical hollow stand 8 on which an electric or other suitable motor 9 is mounted with its shaft disposed vertically 60 and having thereon fan-blades 10 set to drive the air upward in the column. This hollow stand 8 is closed at the top, but is open at the bottom where it is of an outside diameter to fit just inside the adjacent edge of the 65 column 1. The two shells 1 and 8 may be fastened together in any suitable manner, but, preferably by the bolts 11, as shown.

In use, when the device is stood on a flat supporting surface, the hollow shell 8 constitutes a closed chamber in which may be placed a pan 12 containing a cake or block of ice 13 so as to chill the air within and the shell itself. Consequently, by providing a multiplicity of intake openings 14 near the 75 lower end of the outer shell 1, the air drawn into said outer shell by the action of the fan-blades 10 travels in contact with said inner shell 8 and is thereby cooled, after which it is forced out through a series of apertures 80 15 provided near the top of the column and below the restricted throat 2.

The chilled air discharged through the apertures 15 is dissipated laterally at a considerable elevation from the floor and at 85 least above the heads of the occupants of the room and causing a circulation of the air in the room. The cover-plate 4 may be closed entirely during the operation of the device or opened to any desirable degree to 90 allow more or less air to be forced out of the column, the overhanging marginal portion of said cover-plate acting to deflect the discharged air laterally. The device may also be used to facilitate forced ventilation 95 by taking in the air from outside of the room, it being only necessary to apply a suitable conduit to the openings 14 of the column 1 so as to supply pure air as well as modify the temperature in warm weather. 100

In practice the intake openings 14 are preferably of larger area combinedly than the openings 15 so that the air is forced out through the latter under pressure, and any relief therefrom or to equalize the intake 105 and outlet may be brought about by adjustment of the cover-plate 4.

There is no circulation or commingling of the air in the inner shell 8 with that in the outer shell 1, but a vent aperture or a 110 series 16 thereof may be provided near the bottom of said inner shell 8.

2 As shown, horizontally disposed cross-tubes 17 are provided in the inner shell 8, so that some of the air in the outer shell 1 may pass therethrough, and whereby the 5 contactual surface of the cooling element is materially increased.

Preferably, a base-pan or tray 18, having an upturned marginal flange 19, is provided to support the ice-pan 12, and upon 10 which also the inner and outer shells 1 and 8 are detachably seated. By this arrangement, of course, the shells have to be lifted off the base-pan or tray to place or remove the ice-pan, but it is obvious that in some 15 cases doors may be provided in the shells so that access may be had to the interior of the inner shell without disturbing the position of the device. So, too, an opening 20 may be provided in the outer shell 1 in the 20 region of the motor 9 to gain access to the latter, which opening may be kept normally closed by a sleeve 21 or a suitable door.

The column may be ornamented in various ways as an attractive article of furniture, and it may be placed conveniently in the room where it will not obstruct vision. On it may be mounted electric lamps 22, as shown, which may be colored if desired, particularly when the device is used in a motion picture theatre, in which case they may be red or green as lights are now usually provided therein. So, too, the device may be used as a display stand, and flags 23 may be mounted adjacent to the apertures 15 so that the air discharged therefrom will cause the flags to flutter, or other operable devices 35 may be substituted therefor.

Obviously, the device admits of considerable modification in its entirety without in 40 the least departing from the spirit of the invention. Therefore, it is not limited to the specific structure shown in the drawing.

What is claimed is:

1. In a device of the character described, 45 a hollow column which tapers upward, terminating with a restricted throat and flared mouth, an adjustable closure for said mouth, a cooling element in the lower portion of said column, and mechanical means for creating a forced draft upward through said column, said column having air intake openings near its bottom whereby the air entering the column passes in contact with said

cooling element, and outlet openings near its top, but below the throat, said outlet 55 openings being of lesser area than said intake openings.

2. In a device of the character described, a hollow column having an air inlet in the 60 lower portion and an outlet in the upper portion thereof, a temperature-controlling element comprising a hollow radiating shell, located in the lower part of said column so that the air entering the column comes in 65 contact with the surface of said shell, and a motor-actuated fan mounted in said column intermediate said shell and the air outlet of the column and arranged to drive the air upward. 70

3. In a device of the character described, a hollow column which tapers upward, a cooling element in the lower part of said column, the same comprising a closed hollow shell which tapers upward and is provided with transverse tubes extending therethrough, mechanical means for creating a forced draft upward through said column, and said column having an annular series of apertures near its bottom and a similar 80 series of apertures near its top, the upper end portion of said column terminating with a flared mouth and having a closure whose marginal portion overhangs the lip thereof, 85 said closure being adjustably mounted longitudinally with respect to the axis of the column.

4. A portable air cooling and circulating device, comprising a base-pan, a hollow, upwardly tapering column supported on said 90 base-pan, said column having an air intake near its bottom and an outlet near its top, a hollow, upwardly tapering shell closed throughout except at its bottom, the bottom 95 edge portion of said shell fitting the bottom edge portion of said column, said shell adapted to contain a refrigerating agent supported on said base-pan, and mechanical 100 means for creating a forced draft upward through said column whereby the air entering the column passes in contact with the outer surface of said shell and is discharged in chilled conditions through the outlet of said column.

Signed at St. Louis, Missouri, this 12th 105 day of March, 1919.

GEO. L. MENK.
